UNITED STATES PATENT OFFICE

BYRON B. MINNIUM, OF CHICAGO, ILLINOIS, ASSIGNOR, BY MESNE ASSIGNMENTS, TO
STORY & CLARK RADIO CORP., OF CHICAGO, ILLINOIS, A CORPORATION OF DELA-
WARE

RADIO RECEIVING APPARATUS

Application filed November 25, 1927. Serial No. 235,521.

This invention relates to radio receiving sets of the kind in which, for one reason or another, there is ordinarily some liability of a hum or ripple voltage in the amplifier out-

put.

Generally stated, the object of the invention is to provide an improved construction and circuit arrangement whereby the said hum or ripple voltage is prevented, or at least greatly reduced, even when alternating current is employed for heating or energizing the filament of the amplifier, thus improving the receiving qualities of a receiving set of this kind.

It is also an object to provide certain details and features of improvement and combinations tending to increase the general efficiency and the desirability of a radio receiving set of this particular character.

To these and other useful ends, the invention consists in the matters hereinafter set forth and claimed, and shown in the accompanying drawings, in which the single diagram illustrates a radio receiving set involving the principles of the invention.

As thus illustrated, the invention comprises an ordinary aerial 1, which is connected to ground 2 through the primary 3 of an ordinary induction or repeating coil. The secondary 4 of said induction coil and the adjustable condenser 5 are connected in parallel or in shunt of each other, at the points 6 and 7, and the point 6 is connected by a conductor 8 to the grid 9 of the first vacuum tube or amplifier, while the junction point 7 is connected by the conductors 10 and 11 to the ground 2, as shown. The conductor 10 is also connected through the conductor 12 with the negative pole of the battery 13, while the positive pole of this battery is connected by the conductor 14 with the intermediate point 15 on the resistance 16, as shown. The filament 17 of said tube or amplifier has its terminals connected to the opposite ends of the secondary 18 of the transformer or induction coil 19, and a resistance 20 is connected in bridge across the filament circuit, as shown. The conductor 12 is connected through a resistance 21 with the adjustable point 22 on the resistance 20,

whereby the negative pole of the battery 13 is connected to the filament. The plate 23 of the tube or amplifier is connected by a conductor 24 with the junction point 25, whereby said plate is connected to one terminal of the resistance 26, and with one terminal of the primary 27 of the second induction or repeating coil. The lower terminals of the resistance 26 and primary winding 27 are connected together by a conductor 28, as shown. The resistances 16 and 26 are connected together in any suitable manner, for example, by a slide having movable contacts 29 and 30 for engaging said resistances, respectively. The input circuit of the second stage of amplification includes the secondary 31, as shown.

It will also be seen that the diagram, which is illustrative of one form of the invention, includes a primary 32 for the transformer 19, to which is connected a plug 33 that can be inserted in any electrical base or receptacle which has connection with a source of alternating current supply. In this way, the transformer coils 18 and 32 are adapted to co-operate to supply alternating current to the filament 17 of the first stage of amplification; and it will be seen that another secondary 34 is also included in the transformer 19, so that the filament 35 of the second stage of amplification is also heated or energized by alternating current.

In ordinary receiving sets of this kind, the control of gain (or volume) is usually had by varying the filament (cathode) or plate (anode) potential. In the use of tubes or amplifiers in which the filament or electron emitting element is heated by alternating current, normal operating values of plate and filament voltage must be maintained in order to prevent hum or ripple voltage in the amplifier output. The circuit arrangement shown and described, which is illustrative of one form of the invention, serves to hold the plate voltage (and therefore the plate current) constant, but varies the amount of plate energy flowing through the transformer or induction coil primary 27 to which it is connected. If primary 27 is relatively small in value, then resistance 16 may be omitted.

When the resistance of the primary coil 27 is high, the fixed point 15 must be placed near the lower end of the resistance 16, and the resistance of this coil 16 must be so proportioned as to always maintain a fixed value of resistance between this fixed point 15 and the plate 23 of the tube or amplifier.

It is obvious that the invention may be employed in connection with any output primary alone, or in connection with two or more output primaries, as may be desired. But whether the invention is employed in one form or another, the adjustment of the contact points 29 and 30 (or the contact 30 alone if the resistance 16 is not necessary) can be employed to eliminate any hum or ripple voltage in the amplifier output, while at the same time varying the volume. In other words, the object of the invention is to provide means for easily and satisfactorily varying or changing the volume without producing objectionable hum or ripple voltage.

It will be seen that the zero point on resistance 16 is reached when the movable points 29 and 30 are moved downward until point 29 is opposite point 15 on the resistance. Thus, while one resistance is increasing, the other resistance is decreasing, so to speak, by adjustment of the points 29 and 30 in either direction, in any range of adjustment above the fixed point 15, connected with the source of plate potential. In other words, each resistance varies reversely to the other, for as one increases, the other diminishes, and vice versa, according to the direction in which the points 29 and 30 are adjusted. The point 15 can be attached wherever necessary on the coil 17, depending upon the resistance of the primary 27 of the transformer.

Without disclaiming anything, and without prejudice to any novelty disclosed, what I claim as my invention is:

1. In a radio receiving set, an amplifier output induction coil primary having a resistance in shunt thereof, and having the source of plate potential connected to a variable point between the ends of said resistance, including a variable resistance between said source and said first mentioned resistance.

2. In a radio receiving set, an amplifier output induction coil primary having a resistance in shunt thereof, and having the source of plate potential connected to a variable point between the ends of said resistance, including a variable resistance between said source and said first mentioned resistance, there being a variable point for engaging said variable resistance between the ends thereof, and said variable points being adjustable in unison.

3. In a radio receiving set, an amplifier output induction coil primary having a resistance in shunt thereof, and having the source of plate potential connected to a va-

riable point between the ends of said resistance, including a variable resistance between said source and said first mentioned resistance, there being a variable point for engaging said variable resistance between the ends thereof, and said variable points being adjustable in unison, said variable points and said resistances being so relatively arranged that as more of one resistance is included in the plate circuit, less of the other resistance is included therein, and vice versa, by the adjustment of said points in unison in one direction, or in the opposite direction.

4. In a radio receiving set, an amplifier output induction coil primary having a resistance in shunt thereof, and having the source of plate potential connected to a variable point between the ends of said resistance, including a variable resistance between said source and said first mentioned resistance, with means whereby one resistance varies reversely to the other.

5. In a radio receiving set, an amplifier output induction coil primary having a variable resistance in shunt thereof, so that the coil and more or less of said resistance are in multiple in the plate circuit, and a variable resistance in series with said resistance in the plate circuit.

6. A structure as specified in claim 5, having means whereby each resistance is necessarily variable in unison with the other, but reversely thereto.

7. A structure as specified in claim 5, said source being connected to an intermediate point on said last mentioned resistance.

8. A structure as specified in claim 5 having means whereby any portion of said resistance which at any time is not in shunt of said primary is in series therewith in the plate circuit.

Specification signed this 22nd day of November, 1927.
